GEORGE F. WILSON, OF EAST PROVIDENCE, RHODE ISLAND.

Letters Patent No. 75,832, dated March 10, 1868.

IMPROVEMENT IN BURNING BONES FOR THE MANUFACTURE OF ACID PHOSPHATES.

The Schedule referred to in these Letters Patent and making part of the same.

TO ALL WHOM IT MAY CONCERN:

Be it known that I, GEORGE F. WILSON, of East Providence, in the county of Providence, and State of Rhode Island, have invented a new and improved Method of Burning Bones to Whiteness for use in the Production of Horsford's Acid Phosphates for Culinary Uses: and I do hereby declare that the following is a full and exact description thereof, reference being had to the accompanying drawings, and to the letters of reference marked thereon.

The object of my invention is to obtain bones burned to whiteness. To attain this object it is necessary that there be continuous intense heat and ready access of air. When I first began to make Horsford's pulverulent acid phosphates, I burned the bones in what is called a reverberatory furnace, the ordinary form of furnace described in standard works. My object then was to consume all the organic constituents of the bone, and to obtain a purely white phosphate of lime, to be employed as described in Horsford's patent. Without the expenditure of large quantities of fuel, and the employment of expensive and skilled laborers, I found that I succeeded but imperfectly in the attainment of my object, and even under these conditions the result was far from satisfactory. With the plans for leaching which I then followed, it was necessary that the bones should be burned as nearly white as possible, an indication that all the organic elements had been consumed. If sulphur and cyanogen compounds and protoxide of iron, as such, were left in but small quantities in the burned bones, the phosphoric acid leached from them was discolored and impure.

I found the ordinary reverberatory furnace objectionable in many respects.

First. It was expensive to keep it in operation.

Second. The products of the combustion or burning of the bones escaped into the atmosphere in large quantities, and were offensive to the neighborhood.

Third. If the bones were left on the sole of the furnace without frequent stirring, they would remain unburned. If they were frequently stirred, so as to bring them into contact with the air to whiten them, the furnace would cool off, and the whole mass would assume a grayish white tint, which it would be difficult afterwards to remove.

Fourth. If the furnace were driven to a great heat, so as to whiten the whole mass, then some portions of the bone would be converted into an insoluble pyrophosphate of lime, of little or no value, and thus a loss would ensue.

To burn bones as nearly white as desired, and in a large way, for the manufacture of Horsford's acid phosphates, I discovered that it was necessary that they should be subjected to a steady, long-continued, uniform heat, with sufficient air to secure perfect combustion without danger of cooling off the furnace, and that it was desirable to attain these results and consume the greater part of the smoke at the same time.

These ends are gained by the employment of a furnace of particular shape and construction, and of sufficient interior capacity, for the ready mixing of an adequate measure of air with the gases distilled from the bones, before the gases leave the space where the heat of the combustion can reach the bones. Without the heat arising from the burning of the gases which the bones yield, it would be quite impracticable to obtain the necessary whiteness where any considerable quantity of bones is to be handled at one time.

The accompanying diagrams exhibit the form and construction and arrangement of flues which I have invented, and which have been found to meet the wants of the case.

Figure 1 presents a vertical section, parallel to the front face of the furnace.

Figure 2 presents a section at right angles to that shown in fig. 1, and exhibits its flues and fire-space under the floor or sole of the furnace, and over the arched roof of the furnace.

Figure 3 presents a ground plan, showing the fire-grate and the arrangement of fire-passages under the sole.

Figure 4 exhibits the flues over the arched roof of the furnace.

S is the sole, of fire-brick. o o o is the arched roof of the furnace, with the intervening spaces for flues. F' F' F'' F'' are the channels through which the heated products of combustion traverse the spaces over the arched roof, and by which they are conducted to the chimney. F F are the openings, through which the flames from the grate A, having traversed the flues e e e, under the sole, enter the furnace-chamber from the upright flues e' e'. G is the exit-flue over the furnace-chamber, extending to the chimney-flue H. x x are passages,

which allow the flames and products of combustion to pass from the front of the furnace-chamber upwards into the flues F' F', over said chamber, and out through G into the chimney H. D is a sliding damper in the chimney H. K is the ash-pit, and may have a water-trough, W, underneath.

The mode of operation is the following: After the furnace has been thoroughly heated, shin-bones, jaws, knuckle-bones, or skulls of beeves, (each class by itself,) are spread over the sole or floor of the furnace. The water is at once driven out from the bones by the heat, and the fatty and animal matters begin to vaporize. Air is admitted in quantity sufficient to insure the complete combustion of the carbon. When this is done no black smoke issues from the furnace. If an excess of air is admitted it will chill the bones, and thus prevent their becoming white. The admission of air is regulated by raising or lowering the door B, and opening or closing the damper D. The flame from the fire-box, after traversing the flues e e e e under the sole S, and rising through the vertical flues e' e', enters the furnace-chamber at F F'. Here it meets the gases escaping from the bones, and the air from without, and mingling with them, and burning the gases, passes up through apertures x x into F' F', and G at length escapes through the chimney H.

It is indispensable that the temperature at which the distillation goes forward be not for once intermitted, since, in the event of the heat of the bones falling below a certain high point, it is impossible, with any practicable heat thereafter, to burn them white. With the aid of a long spatula the bones are from time to time turned over, so as to facilitate the access of the air. The flat bones, like the jaws, and the round bones, like the shins, require unequal times for burning white, and for this reason, as indicated above, it is better to burn each class by itself. When the bones are wholly white they are withdrawn into iron receptacles, and their place immediately supplied with fresh bones. When a charge is taken out and renewed, the damper is closed, to retard the heat during the process of renewal.

I claim, and desire to secure by Letters Patent of the United States—

1. The new and improved furnace, substantially as above described, whereby the flame is carried under the hearth thereof, and is introduced into the chamber which contains the bones, where it burns with the combustible products of distillation and atmospheric air, admitted in regulated quantities, and thus, while the offensive odors are destroyed, the heat of the chamber is intensified to the degree required for the production of white-burned bone, without converting the same into an insoluble pyrophosphate of lime; the flame, and products of combustion then passing into the flues over the chamber into the escape-flue.

2. The new and improved process of burning bones white, whereby I am enabled to obtain from them a pure phosphate of lime, in the manner and for the purpose above specified.

GEO. F. WILSON.
